UNITED STATES PATENT OFFICE.

SIGMUND STERNAU AND CHARLES NELSON, OF NEW YORK, N. Y., ASSIGNORS TO S. STERNAU & CO., OF BROOKLYN, NEW YORK, A COPARTNERSHIP.

DESIGN FOR A VAPOR-STOVE.

No. 39,968.

Specification for Design.

Patented May 4, 1909.

Application filed February 9, 1909. Serial No. 477,037. Term of patent 14 years.

To all whom it may concern:

Be it known that we, SIGMUND STERNAU, a citizen of the United States, and a resident of the borough of Manhattan, city, county, and State of New York, and CHARLES NELSON, a subject of the King of Sweden, and a resident of the borough of Brooklyn, county of Kings, city and State of New York, have invented a new, original, and ornamental Design for Vapor-Stoves, of which the following is a specification, reference being had to the accompanying drawing, forming part hereof, which shows a perspective view of the design.

The design comprises a rectangular body with legs of ogee shape. From one side of

the body arises a curved neck with a fuel reservoir of cylindrical shape. On the opposite side from the neck is a stem, and circular handle. In the center of the body is a burner of circular shape, and around the burner is a ring, having a number of curved radiating fingers.

We claim:

The ornamental design for a vapor stove as shown and described.

SIGMUND STERNAU.
CHARLES NELSON.
